UNITED STATES PATENT OFFICE

91,920

DESIGN FOR A FLEXIBLE POCKET RECEPTACLE

Warner R. Buxton, Longmeadow, Mass.

Application March 24, 1933, Serial No. 47,576

Term of patent 14 years

To all whom it may concern:

Be it known that I, WARNER R. BUXTON, a citizen of the United States, residing at Longmeadow, in the county of Hampden and State of Massachusetts, have invented a new, original, and ornamental Design for Flexible Pocket Receptacles, of which the following is a specification, reference being had to the accompanying drawing, forming part thereof.

Fig. 1 is a front elevational view of a bill fold embodying my new design; and

Fig. 2 is an end elevational view thereof.

The design appears wholly on the front side of

the bill fold shown in Fig. 1,—the reverse side being plain. The design is essentially characterized by the configuration of the more or less triangular flap appearing in the right hand half of the bill fold shown in Fig. 1 and the radiating relationship between the marginal edges of this flap and the marginal edges of the parts immediately adjacent thereto.

I claim:

The ornamental design for a flexible pocket receptacle substantially as shown and described.

WARNER R. BUXTON.
